HAIR CURLER AND BOBBIE PIN HOLDER

Edward Kantor, New York, N. Y.

Application June 17, 1938, Serial No. 214,328

3 Claims. (Cl. 132—33)

This invention relates to improvements in hair curls and more particularly to a new and improved device useful in the curling of hair for facilitating positioning of a bobbie pin on a hair curl.

One of the important difficulties in hair curling procedure as presently practiced is that insertion of the bobbie pin around the loops of a hair curl frequently causes movement in position of the loops of hair and accordingly, the resultant curl is frequently unsatisfactory, if not unsightly in appearance. The difficulty in positioning the bobbie pin on the curl results from engagement of the shorter or crinkled portion of the bobbie pin with interior portions of the hair curl, whereby certain loops of hair forming the curl are moved out of proper position.

It is among the more important objects of the present invention to provide means for facilitating insertion of bobbie pins in looped hair curls whereby the crinkled shorter arm of the bobbie pin is guided within the hair curl in a manner precluding engagement of the crinkled portion of the bobbie pin with interior parts of the curl prior to removal of the curl from the device.

Another important object of the present invention is to provide a device comprising in combination, a curl bobbin and an arm cooperating with said bobbin for facilitating a hair curl in position thereof.

An important advantage of the novel hair curler and bobbie pin positioning device according to the instant invention is that it permits formation of curls very close to the scalp and positioning of a bobbie pin on the side of the curl next adjacent the scalp whereby coiffures of novel appearance can be produced.

Among the features of the device according to the present invention are the simplicity of the parts thereof, the ease with which the elements can be assembled to form the device, and the ruggedness of the resultant device whereby economies during manufacture and assembly are facilitated and longevity of useful life of the device is at least largely promoted.

Other objects, advantages and features of the device according to the present invention will be apparent to those skilled in the art during the course of the following description.

Regarded in certain of its broader aspects, the present invention comprises a hair curling device including a hollow bobbin, a spring pressed arm slidably mounted on said bobbin adapted to being positioned upon a portion of a curl wound on said bobbin, a retractable bobbie pin holder axial-

ly slidably mounted within said bobbin and means for simultaneously positioning a bobbie pin carried on said holder upon a hair curl wound on said bobbin while said arm is moved from said curl.

In order to facilitate a fuller and more complete understanding of the present invention, a specific embodiment thereof will be hereinafter described, it being clearly understood, however, that the illustrated embodiment is given solely by way of example and is non-limitative upon the scope of the present invention, except as expressed in the subjoined claims.

Referring then to the drawing:

Figure 1 is substantially a side elevational view of the now preferred embodiment of the instant invention, showing same with a bobbie pin in position in the pin holder thereof and with a hair curl wound upon the bobbin.

Figure 2 is substantially a side elevational view of the device illustrated in Figure 1, showing a hair curl in position thereon and the bobbie pin holder in retracted position.

Figure 3 is essentially a vertical sectional view of the device illustrated in Figure 1, exhibiting internal parts thereof.

Figure 4 is a front elevational view of the device shown in Figure 1, and

Figure 5 is essentially a vertical sectional view of Figure 3, taken along the line 5—5.

Referring now particularly to Figures 1 and 3, it will be noted that the device comprises a hollow substantially cylindrical member 10, one portion of which generally designated by the numeral 11, provides a bobbin and the other portion of which generally designated by the numeral 12, providing a handle. The end part of the portion 12 carries a cap 13 having knurled sides for facilitating rotation of the member 10 as will be hereinafter described.

A longitudinal slot-like opening 14 is formed in the portion 12 of the member 10 and extends from an intermediate part of said member to the end thereof normally closed by the cap 13.

An annular member 15 having upstanding flanged end parts 16 is slidably mounted on exterior parts of the cylindrical member 10 and includes a radially extending stop 17 extending through the slot-like opening 14 in the member 10 whereby the sliding movement of the annular member 15 with respect to the bobbin portion 11 of the member 10 is restricted. An arm 18 carried on the pivot 20 mounted in standards 21 and 22 formed on the annular member 15 is normally spring pressed against the bobbin portion 11 of

the member 10 by means including the spring 23 mounted on the pivot 20 substantially as shown in Figures 3 and 5.

It is to be noted that the arm 19 is substantially co-extensive with the bobbin portion 11 of the member 10 and is adapted to press against an end portion of a strand of hair positioned on the bobbin for winding a curl thereon substantially as shown in Figure 1. It will be noted that the arm 19 is provided with a handle portion 25 for facilitating movement thereof on the pivot 20.

A freely rotatable rod 27 positioned within the cylindrical member 10 is provided with an annular groove formation 28 near an end portion thereof adapted to receive and engage with the stop 17 carried on the annulus 15, whereby sliding movement of the annulus results in sliding movement of the rod, although rotative motion of the rod with respect to the annulus is not inhibited. An end portion of the rod 27 projects through the open end of the member 10 nearest the bobbin portion thereof and carries an arm generally designated by the numeral 30, which is movable into fully extended position by positioning the annular member 15 against the end portion of the slot 14 formed in the member 10 substantially as shown in Figures 1 and 3. The arm 30 comprises a shorter channeled portion 31 for receiving the crinkled end part 32 of the bobbie pin 33 and a bifurcated projecting arm 34 adapted to engage with the straight arm 35 of the bobbie pin 33 substantially as shown in Figures 1 and 3. It is to be noted that the shorter portion 31 of the arm 30 is channeled to receive the bent-up end part of the crinkled portion of the bobbie pin whereby the pin is disposed obliquely relative to the arm 30 and that the arms of the pin separated relative to each other substantially as shown.

In use, the end part of a strand of hair is placed against the bobbin portion 11 of the cylindrical member 10 beneath the spring pressed arm 19 and the member 10 rotated whereby a hair curl is formed thereon substantially as shown in Figure 1. Winding of the curl on the bobbin is facilitated by gripping the knurled handle 13 and the projecting arm 30 carrying the bobbie pin 33. When the curl has been formed on the bobbin, the annulus 15 is moved toward the knurled handle 13 whereby the sliding rod 27 is retracted within the bobbin and the pin 33 positioned with the straight arm 35 thereof resting upon the curl substantially as shown in Figure 2. The curl of hair is then removed from the bobbin by sliding motion thereof and the operation is thus completed. It is to be noted that the crinkled part 32 of the bobbie pin 33 is positioned within the curl by the hereinbefore described operations of the device according to the present invention. It is also to be noted that the bobbie pin 33, although initially held obliquely relative to the axis of the bobbin, is moved into substantial parallelism relative to the axis of the bobbin by retraction of the sliding rod removing the bobbie pin, whereby accidental or undesired engagement of loops of hair forming the curl with the portion 35 of the bobbie pin 33, is at least largely precluded.

It is to be understood that this improvement is capable of extended application and is not confined to the exact showing of the drawing nor

to the precise construction described and, therefore, such changes and modifications may be made therein as do not affect the spirit of the invention nor exceed the scope thereof as expressed in the appended claims.

What is claimed as new is:

1. A hair curling device of the type described comprising a hollow cylindrical member providing, near one end thereof, a handle element, and, near the opposite end thereof, a bobbin; an axially sliding annulus mounted on said member between the handle and bobbin portions thereof; and means for holding a bobbie pin for engagement with a hair curl wound on said bobbin, said means comprising a freely rotatable rod, slidably mounted within said hollow member, connected to and movable with said annulus, and a retractable projecting formation carried on one end of said rod for holding a bobbie pin disposed obliquely relative to the axis of rotation of said cylindrical member.

2. A hair curling device of the type described comprising a hollow cylindrical member providing, near one end thereof, a handle element, and near the opposite end, a bobbin; an axially sliding annulus mounted on said member between the handle and bobbin portions thereof; and means for holding a bobbie pin for engagement with a hair curl wound on said bobbin, said means comprising a freely rotatable rod, slidably mounted within said hollow member, connected to and movable with said annulus, a retractable projecting formation, carried on one end of said rod, extending axially from the interior of the bobbin portion of said cylindrical member, said formation including a channeled member for receiving and engaging with a bent end portion of a bobbie pin, and a bifurcated member engaging with other parts of said pin whereby the bobbie pin is carried on said formation disposed obliquely relative to the axis of rotation of said cylindrical member.

3. A hair curling device of the type described comprising a hollow cylindrical member providing, near one end thereof, a handle element, and, near the opposite end, a bobbin; an axially sliding annulus mounted on said member between the handle and bobbin portions thereof; a spring-pressed arm, pivotally mounted on portions of said annulus, extending over, pressing against and substantially conforming in shape with said bobbin for engaging with and holding an end portion of a strand of hair; and means for holding a bobbie pin for engagement with a hair curl wound on said bobbin, said means comprising a freely rotatable rod, slidably mounted within said hollow member, connected to and movable with said annulus, a retractable projecting formation, carried on one end of said rod, extending axially from the interior of the bobbin portion of said cylindrical member, said formation including a channeled member for receiving and engaging with a bent end portion of a bobbie pin, and a bifurcated member engaging with other parts of said pin whereby the bobbie pin is carried on said formation disposed obliquely relative to the axis of rotation of said cylindrical member.
